UNITED STATES PATENT OFFICE.

ORANGE S. LEE, OF CLINTON, MASSACHUSETTS, ASSIGNOR TO THE CLINTON WIRE CLOTH COMPANY, OF SAME PLACE.

REED-SUPPORTING DEVICE FOR LOOMS.

SPECIFICATION forming part of Letters Patent No. 362,980, dated May 17, 1887.

Application filed September 29, 1886. Serial No. 214,859. (No model.)

To all whom it may concern:

Be it known that I, ORANGE S. LEE, of Clinton, in the county of Worcester, State of Massachusetts, have invented a certain new and 5 useful Improvement in Reed-Supporting Devices for Looms, of which the following is a description sufficiently full, clear, and exact to enable any person skilled in the art or science to which said invention appertains to make 10 and use the same, reference being had to the accompanying drawings, forming part of this specification, in which—

Figure 1 is a diagram showing the method of holding and adjusting the reed, and Fig. 15 2 a side elevation representing a portion of the head of the race-plate detached.

Like letters of reference indicate corresponding parts in the different figures of the drawings.

20 In weaving wire-cloth it is well known that those portions of the dents of the reed or sley which are brought into contact with the weft-wires are rapidly worn away, thereby causing the dents to break and require replacing, or 25 notches to be formed in their edges, in which the weft-wires catch and produce imperfect work.

My invention is designed to obviate this difficulty or objection; and to that end I make 30 use of means which will be readily understood by all conversant with such matters from the following explanation.

In the drawings, A represents the beam of the lathe, B the race-plate, C the bed-plate 35 on which the shuttle travels, and D the reed.

The plate B is provided with a horizontally-arranged head-piece, E, in rear of the beam A, said head-piece being channeled longitudinally, as shown at N, to receive and hold 40 the lower bar or rail z of the reed, and provided with an inwardly-curved lip, x, a space, v, being left between said lip and the bed-plate C for receiving the dents f.

Projecting at intervals from the lower side 45 of the head-piece E there is a series of lugs, H, each of said lugs being provided with a vertically-arranged set-screw, J, having a check-nut, t.

A series of vertically-arranged slots, m, are

formed in the face of the head-piece E, said 50 slots opening into the channel N and respectively extending downward into the lugs H.

An elongated slot is formed in the bottom of the head-piece, above each of the lugs H, said slots opening downwardly through the 55 head-piece, as shown by the dotted lines b in Fig. 2. Disposed in each of these slots there is a T-shaped slide, K, the body of which extends downwardly through the slot above an inwardly-projecting lip, Q, on the lower end 60 of the lug H.

Each of the slides K is provided with a set-screw, M, which passes through the slot m, and is adapted to secure the slide in any desired position, the screw J being designed to 65 adjust the slide vertically and the nut t to secure the screw and prevent it from accidentally loosening or turning out after the slide is adjusted.

In the use of my improvement the reed is 70 placed in a vertical position, and its lower rail or bar z inserted in the channel N of the head-piece E, the dents f passing into the space v between the lip x and plate C. The screws M being loose, the slides K are adjusted 75 by the screws J to bring the reed into proper position, after which the slides are secured by the screws M.

The lip x and plate C act as guards to stiffen and keep the dents in position, or prevent 80 them from being unduly bent in the line of the warp in beating up the weft.

It will be understood that the upper rail or bar z of the reed is to be properly supported or secured; but it is not deemed necessary to 85 show the means employed for that purpose. Neither is it deemed essential to show the other parts of the loom in order to illustrate the improvement in question.

It will be obvious that when the dents become 90 sufficiently worn at any given point by the action of the weft-wires to interfere with their proper working or render them liable to break, the reed may be readily raised or lowered to remove the worn or weakened portions out of the path of the weft, thereby 95 bringing new working-surfaces into use, preventing the delays and bad work incident to

the breakage of dents, and rendering the reed far more durable than when not provided with means for vertical adjustment.

I do not confine myself strictly to the use of screws J M, slides K, and lugs H for adjusting and supporting the reed, as any other equivalent means may be employed for that purpose, if desired. If preferred, the lip x may be omitted in constructing the head-piece.

10 E. The plate C may also be omitted without departing from the spirit of the invention, although it is preferable to use the same.

Having thus explained my invention, what I claim is—

15 1. The combination, with the beam, the bed-plate, and reed, of the race-plate provided with the longitudinally-channelled head-piece adapted to receive and hold the reed, and means for vertically adjusting the reed, substantially as described.

2. The combination, with the beam and the reed, of the bed-plate and the race-plate having a longitudinally-channelled head-piece provided with the inwardly-curved lip to receive and hold the reed, and means for raising or lowering the reed, substantially as described.

3. The combination of the race-plate having a channelled head-piece, said piece being provided with a lip and with elongated and vertical slots, the slides movable in said elongated slots for supporting a reed, and the bolts passing through said vertical slots and engaging said slides, substantially as described.

ORANGE S. LEE.
